Primary Examiner — Susan Moon Lee(74) Attorney, Agent, or Firm — Michael J. Feigin, Esq.; Feigin & Fridman(57) CLAIM

I claim the ornamental design for a foam hair brush, as shown and described.

DESCRIPTION

FIG. 1 shows a bottom and side perspective view of a foam hair brush.

FIG. 2 shows a top and side perspective view thereof.

FIG. 3 shows a bottom plan view thereof.

FIG. 4 shows a top plan view thereof.

FIG. 5 shows a left side elevation view thereof.

FIG. 6 shows a right side elevation view thereof.

FIG. 7 shows a front side elevation view thereof; and,

FIG. 8 shows a back side elevation view thereof.

The circular forms covering the bottom of the brush depict bores.

1 Claim, 8 Drawing Sheets(56)
